UNITED STATES PATENT OFFICE.

ALFRED L. JOHNSON, OF BOARDMAN, WISCONSIN.

QUACK-GRASS DESTROYER

1,280,231.

Specification of Letters Patent.

Patented Oct. 1, 1918.

Application filed April 11, 1918, Serial No. 227,964.

To all whom it may concern:

Be it known that I, ALFRED L. JOHNSON, a citizen of the United States, residing at Boardman, in the county of St. Croix and State of Wisconsin, have invented a new and useful Quack-Grass Destroyer, of which the following is a specification.

My invention relates to quack grass destroyers, and the object is to provide an effective, durable and simple machine for eliminating quack-grass and similar weeds from a field.

In the accompanying drawings; Figure 1 is a side elevation of my improved quack grass destroyer. Fig. 2 is a top or plan view of Fig. 1 with the seat and cover omitted. Fig. 3 is a section on the line 3-3 in Fig. 2. Fig. 4 is an enlarged cross section of one of the rollers, as on line 4-4 in Fig. 2. Fig. 5 is a side view of a portion of one of the rollers. Fig. 6 is a section about as on the line 6-6 in Fig. 4. Fig. 7 is a reduced top view of the main portion of the machine with the cover and seat on it. Fig. 8 is a rear view of one corner of the frame and one of the ground wheels and its lever, and showing also one of the standards 10^a.

Referring to the drawing by reference numerals, 1 designates a horizontal open frame having four lateral studs 2 on which are pivotally retained by cotter pins 3 four upright levers 4, each of which has a supporting wheel 5 riding on the ground when the machine is drawn idle. The studs 2 may be fixed in the frame or may be removably held therein by similar cotter pins 3^a (see Fig. 8). At each side of the machine said levers 4 are pivotally connected by a rod 6 and each front lever is extended upward to form a handle 7 adapted to be engaged in a notch 8 of a bracket 9, which is mounted on the front guard rail 10, said rail being secured to the frame by braces 11 and a bolt 12 through each front post 10^a of the rail. A similar rail 13 is secured to the rear end of a hollow upper frame section 14, which forms the upper part of the frame 1 and is provided with a lid 15; the latter is hinged at 16 and provided with a seat 17 and a cross bar 18 which is spaced from the cover by blocks 19 so that the occupant of the seat may place his toes under the bar and thus feel more safe against being jolted off from the seat or from the machine.

Said upper frame section is held in place by having its front corners provided with

curved horns 20 adapted to be pushed into apertures or lateral notches 21 in the front standards 10^a, and the rear portion of the section is provided with guides 22 (see Fig. 6) 1) straddling the lower frame section 1. 23 is any suitable clevis arrangement for hitching the machine to a team or motor by which to draw it.

Journaled in the lower frame section 1 is a series of parallel transversely arranged rollers 24, each of which when made of wood is reinforced by several metallic collars or bands 25, 26; the collars 26 being at the ends of the rollers are preferably integral with the plates 27 and the journals 28 of the rollers. Each roller is provided with a series of diametrical apertures 29, two and two of which intersect each other at the axis of the roller. In said apertures are inserted a series of metal bars 30, having pointed and curved end portions 31 projecting beyond the rollers where they serve as teeth in uprooting the weeds. The crossed middle portions of each pair of bars 30 are half-and-halved together as shown at 32 in Fig. 6, and are held in such engagement by one or more wedges 33 driven into the space vacated by moving one bar into engagement with the other.

A third frame section 34 is pivoted at 35 to the main frame 1 and arranged to swing up and down some with its rear portion. In said portion is journaled a multiple crank shaft 36, the cranks of which operate a series of kicker bars 37, each of which has its upper end slidably guided in a transverse upper bar 38 of said frame section and its lower end provided with resilient wire fingers 39. On said crank shaft is fixed a sprocket 40, which is driven by a link belt 41 and a larger sprocket 42 which is loosely mounted on one of the rollers 24 and carries a series of spring pressed pawls 43 arranged for engagement with a ratchet wheel 44 fixed on the roller, said arrangement being such that when the machine is drawn forward the crank-shaft will be rotated, and if accidentally pushed backward the crank-shaft will not rotate because the pawls play 45 backward on the ratchet teeth.

Pivoted at 45 to swing in horizontal plane upon the rear end of the main frame are two arms 46, each of which carries a vertically slidable bolt 47, which is retained in 116 the arm by its nut 48 while the head 49 is pressed downward by a spring 50 upon the

parts 34^a of frame section 34, whereby said section is caused to press the tines 39 more firmly into the soil where the latter may be extra hard or dry. When such extra pressure is not required, the arms 46 are swung inward clear of the frame parts 34^a, as shown in Fig. 2; said retraction is performed by two rods 51 and a hand lever 52, said lever being pivoted at 53 and by a rod 54 connected to a beam lever 55 which is pivoted at 56 to a bracket 57 and connected with the rods 51.

As already stated, the wheels 5, levers 4-7, and rods 6 are used only when the machine is drawn idle; for actual operation said parts are either entirely removed from the machine or they may be swung to such a position that the wheels stand clear of the ground and the teeth of the rollers will sink into the ground; as the machine is thus drawn forward the teeth of the rollers will pulverize the soil and thereby loosen the roots of the quack grass from it, whereupon the tines 39 will bring the roots upon the ground, where they will soon die for want of earth and moisture, whereupon they may be raked together and removed or burned.

If anything clogs in the rollers the cover 15 may easily be raised so as to get at the rollers without inverting the machine.

When the machine is again to be drawn idle the wheels 5 are replaced with the levers 4 in almost horizontal position so as to get the studs 2 into their places without lifting the frame; after the studs are thus in place the levers 7 and thereby the levers 4 are swung into vertical position whereby the

machine is raised with its teeth 31 clear off the ground and ready to be hauled like a vehicle.

What I claim is:

1. In a machine of the class described, a horizontally disposed skeleton frame with hitching means at its front end, a series of spaced parallel rollers journaled across the frame and having each a series of teeth adapted to work in the soil, a multiple crank shaft journaled across the rear part of the frame, an apertured transverse frame bar fixed upward and forward of the crank shaft, a series of inclined members journaled one to each crank and having their upper ends guided in the apertured bar and the lower ends provided with tines adapted to pick the roots of the weeds up and leave them exposed upon the ground, and operative connection between one of the rollers and said crank shaft to rotate it.

2. The structure specified in claim 1, said frame being made up of a front section in which the rollers are mounted, and a rear section hinged to the front section to swing up and down rearward of the hinges, said crank shaft and members operated by it being mounted in said rear section, means mounted on the front frame section and arranged to engage the rear section and yieldingly impel it toward the ground, and means for throwing said downward pressing means into active and into idle position as may be desired.

In testimony whereof I affix my signature.

ALFRED L. JOHNSON.
